UNITED STATES PATENT OFFICE

115,374

DESIGN FOR A TEXTILE FABRIC

Curt E. Forstmann, Montclair, N. J.

Application April 7, 1939, Serial No. 84,121

Term of patent 14 years

To all whom it may concern:

Be it known that I, Curt E. Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

The figure is a plan view showing the design.

The design is a series of parallel contiguous warp-wise running stripes, each stripe comprising a series of spaced elongated depressions showing a background of parallel loops extend-

ing transversely of the stripe, the surface of the stripe between and surrounding said depressions being in high relief and showing irregular rough crooked nubby loops intermingling in chain-like appearance, the stripes being wider through said depressions than between said depressions, the depressions appearing in diagonal rows, resulting from longitudinal displacement of adjacent stripes.

I claim:

The ornamental design for a textile fabric, as described and as shown.

CURT E. FORSTMANN.
